UNITED STATES PATENT OFFICE

ARNO ANDREAS, OF MUNSTER, GERMANY

SCREEN FOR DISINTEGRATING MACHINES

Application filed February 23, 1928, Serial No. 256,297, and in Germany April 1, 1927.

My invention relates to screens for disintegrating machines, for instance rotary tube, cylinder and ball mills and the like. It is an object of my invention to improve a screen 5 of this kind.

To this end, instead of the usual screens which are cast from high-class steel, I provide screens composed of bars in the manner of a grid or grate.

10 The output of a disintegrating machine is largely a function of the total area available for the flow of the material from one compartment of the machine to the other. Consequently, for a given area of each opening in 15 the screen and under otherwise equal conditions that screen will yield the most favorable output in which the number of openings is the maximum. However this condition cannot be fulfilled with the present type of 20 screen which is made of high-class cast steel. For with this material it is impracticable to cast small and long openings in as close vicinity as required.

By composing the screen of a plurality of 25 bars in the manner of a grid or grate it is possible to provide any number of openings of any desired size without encountering any difficulties in the manufacture thereof.

In the drawing affixed to this specification 30 and forming part thereof a screen embodying my invention is illustrated diagrammatically by way of example.

In the drawing

Fig. 1 is an axial section of the cylinder of 35 a grinding machine with the new screen inserted therein,

Fig. 2 is a transverse section of the cylinder viewed in the direction of the arrow in Fig. 1, which also indicates the direction of 40 flow of the material,

Fig. 3 is a cross-section of several bars, drawn to a larger scale, and

Fig. 4 is an elevation showing the outer ends of the bars, also on a larger scale.

45 Referring to the drawing, *a* and *b* are compartments of the cylinder which are separated by a screen according to my invention. The screen is composed of a number of independent bars *d* which, as shown in Figs. 2 and 4, are sector-shaped and partly recessed

along their adjacent edges to form openings or slots *e*.

g is a holder of any suitable design, which is here shown as a pair of rings of angle-section engaging the ends of the bars *d*, the inner ends of which are inserted in a boss *f*. Preferably, as shown in Fig. 3, one edge of each bar is beveled at the slots *e* so as to obtain flaring slots. The beveled edges are inclined in the direction in which the cylinder is intended to rotate as shown by the large arrow in Fig. 3, and the slots are extended in the direction in which the material is intended to flow, as indicated by the small arrows in Fig. 3. Ribs *i* may be formed on the bars intermediate the holder *g* and the boss *f* in order to reinforce the bars.

As a rule no machining of the bars is required, only the last bar which is inserted 70 may require machining in order to obtain a proper fit of the bars.

According to this invention the total free area of the screen is considerably larger than in a cast-steel screen, and the proper distribution of the openings or slots is facilitated. Obviously the output of the machine is increased with an increase of the total area available for the flow of the material and by suitable arrangement of the openings constituting the area, or, conversely, for a given 75 output of the machine the area of each opening may be reduced in the screen according to my invention to obtain a finer disintegration.

In case of damage all parts of the screen are readily exchanged.

As compared with cast-steel screens, the efficiency of the grinding operation is considerably increased by forming the bars with sharp edges at the slots and arranging the slots in a favorable manner, both expedients 80 being impracticable for obvious reasons in cast screens.

In particular it is neither possible in a cast screen to provide the required number of openings nor to arrange them in suitable positions with respect to each other, nor to provide the most favorable area for each opening. Consequently this invention brings about a considerable improvement both from 85 the technical and economical points of view.

I wish it to be understood that I do not desire to be limited to the exact details of construction shown and described for obvious modification will occur to a person skilled in the art.

5 5 I claim:—

1. Separator comprising a cylindrical outer shell, a boss fixed in the center of said shell, a pair of rings fixed to said shell in spaced relation and a plurality of individual bars radially juxtaposed in spaced relation with their outer ends loosely inserted between said rings, the inner ends resting loosely on said boss.
- 10 15 2. Separator comprising a cylindrical outer shell, a boss fixed in the center of said shell, a pair of rings fixed to said shell in spaced relation and a plurality of individual bars radially juxtaposed in spaced relation with their outer ends loosely inserted between said rings, the inner ends resting loosely on said boss, one edge of each bar being beveled and inclined in the direction of rotation of said shell.
- 20 25 30 In testimony whereof I affix my signature.
ARNO ANDREAS.
